APPARATUS FOR EXTRUDING MATTER

John Wells, Baltimore, Md., assignor to Western Electric Company, Incorporated, New York, N. Y., a corporation of New York

Application January 10, 1935, Serial No. 1,123

1 Claim. (Cl. 207—16)

This invention relates to apparatus for extruding matter, and more particularly to improvements in cable sheath extruding apparatus.

5 Although not limited thereto, the present invention is particularly applicable to cable sheath extruding presses of the intermittent extruding type, wherein the extruding chamber or press cylinder is filled with a charge of molten metal, 10 such as lead, which is first allowed to cool to an extruding temperature and is then extruded through the die into the form required, for example, cable sheath. When the lead in the press cylinder is exhausted, or nearly so, the 15 extruding plunger is withdrawn and the cylinder is refilled with a fresh charge of molten lead and after the fresh charge is allowed to cool to the proper temperature, the extruding operation is resumed. This cycle of operations 20 is repeated until the entire length of cable is sheathed.

At the end of each extruding cycle, the small portion of the lead charge remaining in the bottom of the cylinder is in a substantially solid condition and, therefore, unless it is substantially free of dross or other impurities, it does not unite satisfactorily with the fresh charge of molten lead. It has been found, however, that a satisfactory union between the 25 lead of successive charges is obtained if, before refilling the press cylinder with a fresh charge of molten lead, the upper surface of the residual portion of the preceding charge is remelted to an appreciable depth to insure that any dross or other impurities that may be contained 30 therein are displaced by the fresh charge and rise to the top surface thereof.

An object of the present invention is to provide, in an extruding apparatus of the above 40 type, practical and efficient means for remelting the residual portion of the metal in the extruding chamber before refilling the chamber with a fresh charge of molten metal.

In accordance with the above object, one 45 embodiment of the invention, as applied to an extruding press of the above mentioned type, comprises means for heating the extruding plunger at or near the end of each extruding cycle so that the residual portion of the metal 50 remaining in the press cylinder is remelted before the plunger is withdrawn to refill the cylinder with a fresh charge of molten metal. Specifically, this means preferably comprises one or more electrical heating elements mounted 55 within a removable end portion of the ex-

truding plunger and adapted to be connected at the proper time with a suitable electrical power supply.

In the accompanying drawing, the invention is disclosed, for example, as applied to a cable sheath extruding press of the intermittent extruding type comprising the usual press cylinder 10 and die block 11 carried by a hydraulic ram 12 slidable in a hydraulic cylinder 13. The extruding cylinder is open at the top and has an opening at the bottom connected to the usual extruding die mounted in the die block 11 and through which the cable to be sheathed is passed. The ram 12 is adapted to be raised to elevate the cylinder 10 to a position wherein 10 a fixed piston or extruding plunger 15 enters the cylinder, after which continued upward movement of the cylinder causes the plunger 15 to press the matter, such as lead, contained in the cylinder through the extruding die and 15 around the cable passing therethrough.

In accordance with a feature of the present invention, the extruding plunger 15 comprises a removable end portion 16 in the form of a plug which is threaded to the body or shank portion 20 of the plunger. Suitably mounted within this removable plug is an electrical heating unit 18. As shown in the drawing, the heating unit 18 may consist of electrical resistance elements 20 mounted within a suitable casing 21 adapted to be cast within the plug 16. Terminal members 25 connected to the resistance elements 20 project upwardly through the plug 16 for connection with electrical conductors 23 which are adapted to be connected with a suitable electrical power 30 supply (not shown).

The extruding plunger 15 is provided with a longitudinal bore 24 through which the conductors 23 are threaded for connection with the heating unit 18. The conductors 23 enter the 40 bore 24 through a radial bore 25 in the upper end portion of the plunger, which portion does not at any time enter the press cylinder.

The operation of the apparatus is as follows:

With the press cylinder in its lowermost position, it is filled with molten lead from a suitable melting kettle (not shown). After a short time is allowed for the charge to solidify, the press cylinder is elevated by the ram 12 causing the plunger 15 to press the lead through the die and 45 around the cable passing therethrough. When the press cylinder reaches its uppermost position the lead charge is extruded down to the point A, leaving a portion or slug 26 of solidified lead in the bottom of the cylinder and in the extruding 50

die. At or near the end of the extruding cycle and before lowering the cylinder to withdraw the extruding plunger, the electrical heating unit 18 is energized to heat the lower end of the plunger sufficiently to remelt the upper surface of the residual slug 26 to an appreciable depth so as to insure that any dross or other impurities that may be contained therein will rise to the top of the succeeding fresh charge. The heating unit 10 18 is then disconnected from its energizing current, after which the press cylinder is lowered in the usual manner to receive a fresh charge of molten lead. The dross or other impurities that may have been contained in the residual slug 15 of the preceding charge, having been released by the remelting of the residual slug as described above, are now free to rise to the top of the fresh charge before the extruding operation is resumed. Thus the lead at the junction of successive charges is free of impurities so that sub-

stantially perfect unions between successive charges are obtained.

It is to be understood, of course, that the extruding plunger is permitted to cool sufficiently before the extruding operation is resumed, and the cooling thereof may be expedited, if necessary, in any well known manner, such as by means of a cooling medium applied to the plunger either externally or internally.

What is claimed is:

In a cable sheath extruding press, an open cylinder for receiving molten metal, a plunger for extruding metal from said cylinder, said plunger being adapted to be withdrawn from the cylinder to permit pouring a fresh charge of molten metal 15 therein, and readily replaceable electrical heating means within the end of the plunger for fusing the surface of the preceding charge prior to withdrawal of the plunger.
